(57) **CLAIM**

The ornamental design for a pet water or food storage unit with stowable bowl, as shown and described.

DESCRIPTION

FIG. 1 is a perspective view of a pet food storage unit with stowable bowl embodying my design, with the end-mounted latches and clips for securing the lid to the container sidewall, the striations along the container sidewall, the end-mounted stop on the dish sidewall, and the complementary scalloped edge section of the container sidewall being shown in broken lines for illustrative purposes only and forming no part of the claimed design;

FIG. 2 is an opposite perspective view of the unit depicted in FIG. 1, with the recessed end section of the dish sidewall and the end cutout section of the container sidewall being shown in broken lines for illustrative purposes only and forming no part of the claimed design;

FIG. 3 is an end elevation view of the unit depicted in FIGS. 1 and 2;

FIG. 4 is a side elevation view of the unit depicted in FIGS. 1-3;

FIG. 5 is an end elevation view of the unit opposite that shown in FIG. 3;

FIG. 6 is a side elevation view of the unit opposite that shown in FIG. 4;

FIG. 7 is top plan view of the unit depicted in FIGS. 1-6; and,

FIG. 8 is a perspective view of the unit similar to FIG. 1, but depicting the bowl swung relative to the container to a pet-access position, with the internal bowl cavity formed by the dish and the stop formed along the upper margin of the dish sidewall being shown in broken lines for illustrative purposes only and forming no part of the claimed design.
